AUTOMOBILE

Jack E. Kenitz, Detroit, Mich., assignor to Chrysler Corporation, Highland Park, Mich., a corporation of Delaware

Application May 11, 1955, Serial No. 35,936

Term of patent 7 years

(Cl. D14—3)

Fig. 1 is a side elevational view of an automobile showing my new design with the side opposite being similar to the one illustrated;

Fig. 2 is an enlarged fragmentary view of a portion thereof; and

Figs. 3, 4, 5 and 6 are fragmentary sectional views taken on the line 3—3, 4—4, 5—5 and 6—6 respectively of Fig. 1.

The characteristic features of my design reside in the portions shown by means of full lines in the drawing.

I claim:

The ornamental design for an automobile, substantially as shown and described.
